BALANCED WELL PUMP

William H. Porter, Phoenix, Ariz.

Application December 7, 1954, Serial No. 473,706

2 Claims. (Cl. 103—183)

This invention relates to pumps, and more particularly to an improved lift pump.

The main object of the invention is to provide a novel and improved lift pump which is simple in construction, which is reliable in operation, and which involves relatively few parts.

A further object of the invention is to provide an improved lift pump which is inexpensive to manufacture, which is rugged in construction, which is smooth in operation, and which is balanced so that it may be easily operated without exertion of excessive force on the driving elements thereof.

Further objects and advantages of the invention will become apparent from the following description and claims, and from the accompanying drawings, wherein:

Figure 1 is a side elevational view, partly in vertical cross section, of an improved lift pump constructed in accordance with the present invention.

Figure 2 is a horizontal cross sectional view taken on the line 2—2 of Figure 1.

Figure 3 is a side elevational view, partly in vertical cross section, of a modified form of lift pump according to the present invention, employing a single cylinder.

Figure 4 is a horizontal cross sectional view taken on the line 4—4 of Figure 3.

Figure 5 is an elevational view of a further modification of a lift pump according to the present invention, to a reduced scale.

Figure 6 is a horizontal cross sectional view taken on the line 6—6 of Figure 5.

Referring to the drawings, and more particularly to Figure 1, 11 generally designates a lift pump assembly, said assembly comprising a first vertical cylinder 12 and a second vertical cylinder 13, said cylinders being interconnected at their intermediate portions by a horizontal conduit 14. An outlet conduit 15 is connected to the top portion of the cylinder 12.

Designated respectively at 16 and 17 are respective partition walls which are formed in the lower portions of the respective cylinders 12 and 13 a substantial distance below the horizontal conduit 14. Designated at 18 and 19 are respective piston rods which extend axially through the cylinders 12 and 13 and which extend slidably and sealingly through the respective partition walls 16 and 17, for example, through respective sealing bushings 20 and 21 provided in the partition walls 16 and 17.

Secured to the lower end of the piston rod 18 is a first piston 22, said first piston being located below the partition wall 16 in the cylinder 12, and secured to the piston rod 18 above the partition wall 16 is a second piston 23. Designated at 24 is a piston which is secured to the piston rod 19 below the partition wall 17 of cylinder 13, and designated at 25 is a piston which is secured to the piston rod 19 above the partition wall 17.

The lower pistons 22 and 24 are provided with respective upwardly opening check valves 26 and 27 which are normally closed but which open when the pressure below the pistons exceeds the pressure thereabove. Designated

2

at 28 and 29 are respective upwardly opening check valves provided in the bottom walls of the respective cylinders 12 and 13, said check valves 28 and 29 being normally closed and being arranged to open responsive to the upward movement of the respective lower pistons 22 and 24, by the suction created by said pistons.

Designated at 30 is a conduit which connects the space between partition wall 16 and the lower piston 22 with the space above the upper piston 23 in the cylinder 12. 10 The conduit 30 is provided with the upwardly opening check valve 31, as shown.

Designated at 32 is a conduit which connects the space between the lower piston 24 and partition wall 17 with the space above the upper piston 25 in the cylinder 13, 15 said conduit 32 being provided with the upwardly opening check valve 33, as shown.

Designated respectively at 34 and 35 are respective vent conduits which are connected to the portions of the respective cylinders 12 and 13 between the partition walls 20 16, 17 thereof and the upper pistons 23, 25 thereof, the vent conduits 34 and 35 extending upwardly to levels substantially above the water level with which the pump is to be employed, for example, above the water level shown at 38 in Figure 1. The top ends of the vent 25 conduits 34 and 35 are open, so that the spaces in the cylinders between the upper pistons and the partition walls 16, 17 thereof are vented to atmosphere.

The top ends of the cylinders 12 and 13 are connected by an upstanding bracket 37 of any suitable shape, for example, of inverted V-shape, as shown, and pivoted to the top portion of the bracket 37 at 40 is a common operating lever 41 which is pivotally connected at 42 and 43 to the top ends of the respective piston rods 19 and 18, as shown in Figure 1.

In operation, the lever 41 is oscillated around its pivotal connection 40, whereby the piston rods 18 and 19 are alternately reciprocated. When the piston 22 is moved upwardly, the piston 24 is moved downwardly, and vice versa. When the piston 22 is moved upwardly, the check valve 28 opens, drawing liquid into the lower portion of the cylinder 12. At the same time, the downward movement of the piston 24 causes the liquid in the lower portion of the cylinder 13 to move upwardly past the piston through the check valve 27.

Thus it will be apparent that any liquid in the space above the piston 22 will be forced upwardly through the conduit 30 and through check valve 31 when the piston 22 is moved upwardly, the liquid thus flowing into the space in cylinder 12 above the piston 23 and being forced upwardly to the outlet conduit 15. While this is taking place, liquid is being forced into the space in cylinder 13 immediately above the piston 24, and since piston 25 is moving downwardly at this time, some of the liquid from cylinder 12 will flow through the conduit 14 into the upper portion of the cylinder 13, which thus acts as a reservoir and which serves the purpose of making the operation of the pump smoother by increasing the total capacity of the cylinders.

On the upward stroke of the piston rod 19, which takes place when the piston rod 18 is moved downwardly, the above action is reversed, the cylinder 13 then providing the lift of the liquid previously admitted into the space above the piston 24, said liquid being moved upwardly through the conduit 32 and check valve 33 and flowing through the conduit 14 into the upper portion of the cylinder 12, the fluid pressure being sufficient to cause the liquid to be discharged from the discharge conduit 15 at the top end portion of cylinder 12.

Thus, discharge action takes place on both upward and downward movements of the handle portion of lever 41, and as a result, a smooth and steady flow of liquid is obtained from the discharge conduit 15.

Since the spaces below the pistons 23 and 25 are vented to atmosphere at all times, there is never any unbalance of pressure immediately below these pistons, whereby the pump is balanced at all times.

In the form of the invention shown in Figures 3 and 4, the pump is designated generally at 11' and comprises a single cylinder 12' containing the piston rod 18'. Secured to the lower end of the piston rod 18' is the lower piston 22', said piston 22' being provided with the upwardly opening check valve 26'. The lower portion of the cylinder 12' is provided with the partition wall 16' through which the piston rod 18' slidably and sealingly extends, as by the provision of a sealing bushing 20'. Secured on the piston rod 18' above the partition wall 16' is the upper piston 23'. A conduit 30' connects the space between the lower piston 22' and partition wall 16' with the space above the upper piston 23', the conduit 30' being provided with the upwardly opening check valve 31'. A check valve 28' is provided in the bottom of the cylinder 12', said valve 28' being normally closed and opening when the pressure below the check valve exceeds the pressure above said check valve, namely, when the piston 22' is moved upwardly, creating a vacuum therebelow.

A vent pipe 34' connects the space immediately below the piston 23' with atmosphere, said vent pipe 34' extending parallel to the cylinder 12' and being open at its top end, the top end of the vent pipe 34' being located above the water line of the well, shown at 38'.

Secured to the top end of the cylinder 12' is the upwardly extending bracket 37', and pivoted to said bracket 37' at 40' is a lever 41', said lever being pivotally connected at 43' to the top end of the piston rod 18'. Secured to the outer end of the lever 41' is the counterweight 45.

As in the previously described form of the invention, oscillation of the lever 41' causes alternate opening and closing of the check valve 26' as the lower piston 22' is moved alternately downwardly and upwardly, causing alternate closing and opening of the check valve 28'. Liquid thus trapped in the lower portion of the cylinder 12' will be lifted upwardly through the conduit 30' and check valve 31' to the upper portion of the cylinder 12', and will be discharged through a discharge conduit 15' provided at the top end portion of the cylinder 12'. The provision of the counterweight 45 facilitates the upward stroke of the handle portion of the lever 41', and thus aids in lifting the liquid upwardly through the device to the discharge conduit 15' thereof. Since there is less resistance to the downward movement of the pistons 23' and 22' than to the upward movement of said pistons, the handle portion of the lever 41' can be moved downwardly to elevate the counterweight 45 with approximately the same amount of force as is required to raise the pistons 22' and 23' to elevate the liquid to the discharge spout 15'.

In the modification shown in Figures 5 and 6, the structure is generally similar to that illustrated in Figures 1 and 2, comprising a pair of cylinders 52 and 53 which are connected at their upper portions by a conduit 54, the cylinder 52 being connected at its upper portion to a discharge conduit 55. The internal structure of the cylinders 52 and 53 is the same as the cylinders 12 and 13 in Figures 1 and 2, the spaces in the cylinders immediately below the upper pistons 23 and 25 thereof being interconnected by a transversely extending conduit 56 which is connected to a vertical vent conduit 57 open at its top end. The top ends of the respective piston rods 19 and 18 in the cylinders 52 and 53 are connected to respective oppositely directed cranks 58 and 59 provided on a crank shaft 60, the top ends of the pistons 19 and 18 being connected to the crank 58 by means of suitable connecting rods 61 and 62 having the wrist pin connections 63 and

64, whereby the rods 18 and 19 are reciprocated responsive to the rotation of the crank shaft 60. The crank shaft 60 may be driven by any suitable means.

As in the form of the invention of Figures 1 and 2, the cylinders 52 and 53 have the conduits 30 and 32 connecting the spaces immediately above the lower pistons thereof with the spaces above the upper pistons thereof, said conduits containing suitable check valves, such as the check valves 31 and 33 of Figure 1. The operation of the form of the pump device of Figures 5 and 6 is similar to that of Figures 1 and 2, since rotation of the crank shaft 60 will cause the piston rods 18 and 19 to reciprocate in opposite directions to provide the pumping action previously described in connection with the form of the invention in Figures 1 and 2.

While certain specific embodiments of an improved lift pump have been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A pump comprising a pair of side-by-side cylinders, 25 conduit means interconnecting the intermediate portions of said cylinders, and an outlet conduit connected to the top portion of one of the cylinders, respective partition walls in the lower portions of said cylinders below said conduit means, respective piston rods extending axially through the cylinders and extending slidably and sealingly through the respective partition walls, respective upper and lower pistons on the rods above and below the respective partition walls, a check valve on each lower piston arranged to open when the pressure below the piston exceeds the pressure thereabove, respective check valves in the bottom portions of the cylinders arranged to open responsive to upward movement of the respective lower pistons, respective conduits connecting the spaces between the partition walls and the lower pistons to the spaces above the upper pistons in the respective cylinders, upwardly opening check valves in said last-named conduits, and common operating means pivotally connected to the top portions of the piston rods.

2. A pump comprising a pair of side-by-side cylinders, 45 conduit means interconnecting the intermediate portions of said cylinders, an outlet conduit connected to the top portion of one of the cylinders, respective partition walls in the lower portions of said cylinders below said conduit means, respective piston rods extending axially through the cylinders and extending slidably and sealingly through the respective partition walls, respective upper and lower pistons on the rods above and below the respective partition walls, a check valve on each lower piston arranged to open when the pressure below the piston exceeds the pressure thereabove, respective check valves in the bottom portions of the cylinders arranged to open responsive to upward movement of the respective lower pistons, respective conduits connecting the spaces between the partition walls and the lower pistons to the spaces above the upper pistons in the respective cylinders, upwardly opening check valves in said last-named conduits, a common operating element drivingly connected to the top portions of the piston rods, and vent means connecting the portions of the cylinders between said partition walls and upper pistons to the atmosphere at a level above said first-named conduit means.
